UNITED STATES PATENT OFFICE.

ANDREW A. SCHRAMM, OF CHELTENHAM, PENNSYLVANIA.

SIGN.

1,095,739.

Specification of Letters Patent.

Patented May 5, 1914.

Application filed October 4, 1913. Serial No. 793,333.

To all whom it may concern:

Be it known that I, ANDREW A. SCHRAMM, a citizen of the United States, residing at Cheltenham, in the county of Montgomery, State of Pennsylvania, have invented a new and useful Sign, of which the following is a specification.

My invention relates to a sign and consists of a frame which is adapted to sustain a sign plate or sign proper in a novel, convenient, practical, simple and inexpensive manner, as will be hereinafter set forth.

The invention is satisfactorily illustrated in the accompanying drawing, but the important instrumentalities thereof may be varied, and so it is to be understood that the invention is not limited to the specific arrangement and organization shown and described.

Figure 1 represents a perspective view of a sign embodying my invention. Fig. 2 represents a side elevation thereof on an enlarged scale. Fig. 3 represents a vertical section thereof, on an enlarged scale, on line *x-x* Fig. 2. Fig. 4 represents a horizontal section thereof, on line *y-y* Fig. 2. Fig. 5 represents a vertical section of a portion taken on the side opposite to Fig. 2. Fig. 6 represents a vertical section of a portion on line *z-z* Fig. 2.

Similar numerals of reference indicate corresponding parts in the figures.

Referring to the drawings: 1 designates a frame which is composed of the top cross member 2, the bottom cross member 3, and the side vertical members 4, and 5 designates a plate which is adapted to have matter printed, painted, or otherwise placed thereon for the purpose of a sign, said plate occupying said frame, it being noticed that said top cross member is closed from side to side so that rain or snow cannot pass therethrough and reach the top of the sign. The bottom cross member 3 is open in vertical direction, forming a channel through which the plate 5 may be introduced into the frame and removed therefrom through said bottom.

When the plate is in position in the frame, it is prevented from dropping and so retained therein by the finger 6 which is passed through openings 7 which bisect the vertical opening in the bottom cross member, so as to be projected under the bottom edge of said plate and thus support the latter, said finger being connected with one end of the resilient arm 8 whose other arm is se-

cured to the bottom cross member 3 of the frame as at 9, leaving the main portion of said arm free to be drawn out and move in forming with the finger 6 a spring catch 60 for the sign plate 5.

In the walls of the bottom cross member 3 of the frame are the recesses 10, which are adapted to receive a finger of an operator, so as to raise the sign plate in locating the same in the frame and hold it there until the finger 6 engages said plate. The frame is adapted to be suspended from a crane or hanger 11 by means of hooks and eyes 12 or other suitable means whereby it may readily swing thereon if so desired.

It will be seen that when the catch is drawn out, the plate may be inserted in the frame from below, and pushed up to the full or required extent by the finger engaging 75 the lower edge of the plate through the recesses 10. Then the catch is let go, whereby the finger thereof extends across said edge and acts as a stop or support on which the plate is rested and a retainer for the plate, 80 it being noticed that the openings 7 form passages through the bottom cross member for the finger 6, and their walls support said finger directly in said member 3 without the employment of keepers for such purpose, 85 and as said passages communicate with the vertical opening in said bottom cross member, when the sign plate is raised to the proper height by the finger inserted in the recess, said plate when let go will rest directly on the finger 6, whereby it will sit properly in the frame and be supported in a simple and practical manner.

It is evident that the plate may be readily removed, turned and restored or substituted 95 by another.

In mentioning the member 5 as a plate, it may be of sheet metal, or in lieu thereof, a piece of card board, wood, or other suitable material.

Having thus described my invention what I claim as new and desire to secure by Letters Patent, is:

1. A frame, a sign plate therein, the bottom cross member of said frame having 105 therein a channel extending vertically through the same adapted to contain the lower portion of said plate, and having a passage extending horizontally through said bottom member in communication with said 110 vertical channel, below the lower edge of said plate, and above the bottom edge of

said member, and a slidable finger occupying said passage and removably supporting said plate.

2. In a sign, a frame, the bottom cross member thereof having an opening therein vertically therethrough, and having an upwardly extending recess in the underside of said bottom cross member, said recess being in communication with said opening, said bottom cross member having also a transversely-extending passage directly therethrough, a finger which freely occupies said passage, and a movable arm having one end connected with said bottom cross member, and the other end resiliently carrying said finger.

3. In a sign, a frame, the bottom cross member whereof has a vertically-extending

opening therethrough, a transversely-extending passage therethrough in communication with said opening, and an upwardly extending recess in its under side leading to said opening and communicating therewith.

4. In a sign, a frame, the bottom cross member thereof having an opening vertically therethrough, a transversely-extending passage directly therethrough, and an upwardly-extending recess in its underside leading to said opening and communicating therewith, a finger which freely occupies said passage, and a resilient arm connected with said member and carrying said finger.

ANDREW A. SCHRAMM.
